ROTARY TILLAGE TOOL

Léon Dufour, Acacias-Geneva, Switzerland

Application August 10, 1937, Serial No. 158,443
In Germany June 30, 1937

13 Claims. (Cl. 97—216)

Spring arrangements, formed by long spirally wound spiral springs, for the tools of motor operated machines for working the soil, wherein the tool itself forms a part of the spring or is secured thereto are known.

These springs are frequently distorted or broken by reason of the strains to which they are subjected during operation. In order to remedy this defect endeavours have already been made to mount the tool, secured to the spring, rotatably about the axis of the spring so that radial strains are taken up by this axis of rotation. In this manner distortions are obviated but not the breaking of the springs which always occurs.

Careful investigation has now shown that these breakages are due to the fact that the inner part subjected to pressure when tensioning the spring, for example when the tool meets an obstruction, is subjected to tensioning to a far-reaching extent on the sudden expansion, after the obstruction has been overcome resulting from the mass of the tool connected to the spring. For example it has been found that the tool, when meeting an obstruction, is moved through a predetermined angle from its normal position opposite to the direction of rotation, always swings back to the opposite side of the normal position substantially through the same angle after the obstruction has been overcome. This action is due to the influence of the mass of the tool connected to the spring. The spring breakages which so frequently occur are also very probably due to resonance phenomena. When for example a tool during its oscillation about its normal position meets with an obstruction, just when it is located at the end of an oscillation, by which the spring is already tensioned, this is subjected to an excessive strain, which may cause a breakage, in consequence of the resultant additional tensioning.

The present invention relates to an arrangement of a tool in combination with a longitudinally spirally wound spiral spring, according to which the tool only acts on the spring in one direction and is freely movable in the opposite direction so that on relaxation of the spring this is not influenced by the movement of the tool.

A form of construction of the subject of the invention is shown by way of example in the accompanying drawing, wherein:

Fig. 1 shows a side elevation.

Fig. 2 shows a plan partly in section.

Fig. 3 is a fragmentary top plan view of a modified form of the construction, and

Fig. 4 is a vertical sectional view taken on the line 4—4 of Figure 3.

The main shaft 10 carries a holder 11 with two apertured lugs 25 for the reception of the ends 17 of the longitudinally spirally wound spiral spring 12.

At the middle portion the spring 12 forms an elongated loop 13 of which the middle portion 14 serves as a stop for the tool 15 which is normally freely movable in the loop. The two ends 16 of the loop approach one another at an acute angle and then extend parallel to one another for a predetermined length 19 so that in the direction thereof they may prevent a movement of the tool resiliently and then with a constant braking action.

On each end 17 of the spring 12, which projects from the lugs 25 of the holder 11, there is fitted an arm 18 provided with a corresponding hole.

Each arm 18 is bent at an angle so that its free end lies transversely to the central axis of the spring 12. At this central axis each arm carries a bearing 23 for a tool-shaft 20 about which the tool is mounted rotatably. In addition cylindrically-shaped jaws 21 are provided on both sides of the bearings 23, these jaws engaging the spring 12. The tool-shaft 20 is prevented from rotation and axial movement by pins 22. The assembly of the parts above described is effected simply by fitting the arms 18, whilst located parallel to the main-shaft 10, on the ends 17 of the spring and then turning them through 90° so that the jaws 21 enter the interior of the spring. After the tool-shaft 20 has been fitted into the bearings 23 relative movement of the arms 18 and the spring 12 is no longer possible. As will be seen from the drawing the whole arrangement is held together solely by the pins 22.

The method of operation of this spring arrangement is as follows:

The tool 15, which is capable of rocking about the tool-shaft 20 and is freely movable in the spring loop 13, normally bears against the middle part 14 of the latter, position shown at A in Fig. 1.

When during normal operation of the implement the tool rotating in the direction of the arrow 24 meets an obstruction, for example on the soil which is to be treated, the spring yields and is tensioned to its full extent so that the tool for example reaches the position B. When the obstruction has been overcome, that is to say for example when the tool during its rotation passes out of the ground, the spring 12 expands

suddenly and naturally moves the tool 15 with it. As, however, the latter moves freely in the loop 13 its mass has no influence on the spring 12 so that the spring returns into its normal position immediately and without any separate strain. The tool, however, continues to move in the loop 13 until it meets the approaching ends 16 thereof of which apply a resilient stopping action thereon (position C). When the tool enters the space 10 between the two parallel parts 19 of the spring 12, it forces them apart and thereby is continuously braked until its movement ceases. In other words the impact of the tool is transmitted through the spring 12 to the holder 11 and there- 15 by is absorbed without shock.

By this arrangement the spring 12, during its expansion, is prevented from being subjected in its internal part by a substantial tensional strain, and thus damaged, by the mass of the tool acting thereon.

Because the kinetic energy of the tool is no longer transmitted to the spring but only its degree of velocity in consequence of the impact on the parts 16. This is absorbed comparatively slowly by the resilient braking action of the parts 19. The resultant stressing or tensioning of the spring is extremely small and the question of resonance phenomena no longer arises.

According to the alternative embodiment of 30 the invention illustrated in Figs. 3 and 4, the construction is the same as illustrated in Figs. 1 and 2 with the exception that the loop 13^b of the spring 12^b is open at its forward end to permit free forward or return movement of the 35 tool 15^b, and with the further exception that, in lieu of constricting the forward end of said loop, as in Figs. 1 and 2, two spring arms 25 are mounted on lugs 24 carried by the holder 11^b and are disposed to have the tool enter therebetween during its return or forward swinging movement, whereby its said movement is resiliently arrested independently of the spring 12^b.

I claim:

1. In a spring arrangement for the tools of 45 motor operated machines for working the soil, the combination comprising a main-shaft, a tool-shaft parallel to the main-shaft, a tool rotatably mounted on said tool-shaft, a spiral spring coiled longitudinally around said tool- 50 shaft, said spring being secured at least at one end thereof to the main-shaft, said spring operatively engaging said tool in one direction of rotation, said tool being adapted to move independently of said spring in the opposite direction of rotation.

2. In a spring arrangement for the tools of 55 motor operated machines for working the soil, the combination comprising a main-shaft, a tool-shaft parallel to the main-shaft, a tool rotatably mounted on said tool-shaft, a spiral spring coiled longitudinally around said tool-shaft, said spring being secured at least at one end thereof to the main-shaft, an elongated loop formed in said spring, said tool engaging with 60 said loop, the arrangement being such that on rotation of the shaft in one direction said loop engages said tool, whilst in the opposite direction of rotation said tool moves freely in said loop.

3. In a spring arrangement for the tools of 65 motor operated machines for working the soil, the combination comprising a main-shaft, a tool-shaft parallel to the main-shaft, a tool rotatably mounted on said tool-shaft, a spiral spring coiled 70 longitudinally around said tool-shaft, said spring

being secured at least at one end thereof to the main-shaft, a loop formed at the middle of said spring, said loop having two parallel sides which are connected together at one end, the other ends being inclined towards one another at an acute angle and then extending parallel to one another in spaced relation, the arrangement being such that when the closed end of the loop engages with the tool the latter is moved, preferably whilst tensioning the spring, whilst when the tool moves away from the closed end of the loop the inclined portions of the loop act as a resilient stop for the tool and the spaced parallel sides extending from the inclined portions apply a braking action to the tool.

4. In a spring arrangement for the tools of 75 motor operated machines for working the soil, the combination comprising a main shaft, a tool-shaft parallel to the main-shaft, a tool rotatably mounted on said tool-shaft, a spiral spring coiled longitudinally around said tool-shaft, said spring operatively engaging said tool in one direction of rotation, said tool being adapted to move independently of said spring in the opposite direction of rotation, arms secured 20 to the main-shaft, the ends of said spring being secured to said arms.

5. In a spring arrangement for the tools of 25 motor operated machines for working the soil, the combination comprising a main shaft, a tool-shaft parallel to the main-shaft, a tool rotatably mounted on said tool-shaft, a spiral spring coiled longitudinally around said tool-shaft, said spring operatively engaging said tool in one direction of rotation, said tool being 30 adapted to move independently of said spring in the opposite direction of rotation, arms secured to the main-shaft, the ends of said spring being secured to said arms, and the tool-shaft being supported from said arms.

6. In a spring arrangement for the tools of 35 motor operated machines for working the soil, the combination comprising a main-shaft, a tool-shaft parallel to the main-shaft, a holder secured to said main-shaft, a pair of apertured 40 lugs located on said holder, a spiral spring surrounding said tool-shaft, the ends of said spiral spring engaging said apertured lugs, said ends projecting from said lugs, a pair of arms mounted one on each extending end of said spring, a pair of bearings located one in each arm, a tool-shaft mounted in said bearings, said tool-shaft extending through said spring, jaws on said arms, said jaws engaging with the opposite ends of said spring, means preventing said tool-shaft 45 from rotating or moving axially in said bearings, a loop in said spring, and a tool rotatably mounted on said tool shaft and engaging said loop.

7. In a spring arrangement for the tools of 50 motor operated machines for working the soil, the combination comprising a main-shaft, a tool-shaft parallel to the main-shaft, a holder secured to said main-shaft, a pair of apertured lugs located on said holder, a spiral spring surrounding the tool-shaft extending longitudinally 55 to the said main-shaft, the ends of said spiral spring engaging said apertured lugs, said ends projecting from said lugs, a pair of arms mounted one on each extending end of said spring, a pair of bearings located one in each arm, the tool-shaft mounted in said bearings, said tool-shaft extending centrally and axially through 60 said spring, jaws on said arms, said jaws engaging with the opposite ends of said spring, means preventing said tool-shaft from rotating or mov- 65

ing axially in said bearings, a loop in said spring, and a tool rotatably mounted on said tool-shaft and engaging said loop.

8. A spring arrangement according to claim 5 6, wherein the loop has parallel sides and is closed at one end, the other ends of the parallel sides approaching one another at an acute angle and then extending parallel to one another in spaced relation.

10 9. In a spring arrangement for the tools of motor operated machines for working the soil, the combination comprising a main-shaft, a tool-shaft parallel to the main-shaft, a tool rotatably mounted on said tool-shaft, a spiral 15 spring coiled longitudinally around said tool-shaft, said spring being secured at least at one end thereof to the main-shaft, said spring operatively engaging said tool in one direction of rotation, said tool being adapted to move independently of said spring in the opposite direction, a stop secured to the main-shaft to limit the movement of the tool in said last direction.

10. The combination as set forth in claim 1 25 in which arms for supporting the tool shaft are pivoted to the holder for swinging movements between operative and inoperative positions, and

in which jaws are provided on said arms to enter the ends of the spring when said arms are swung to their operative positions.

11. The combination as set forth in claim 1 5 including a resilient abutment separate from the spring to arrest movement of the tool when the latter moves independently of the spring.

12. The combination as set forth in claim 1 10 in which arms for supporting the tool shaft are pivoted on the ends of the spring projecting from the holder for swinging movements between operative and inoperative positions, and in which jaws are provided on said arms to enter the 15 ends of the spring when said arms are swung to their operative positions for supporting the tool shaft.

13. In a rotary tillage tool, the combination, comprising, a main shaft, an annular holder fitted to the main shaft, an offset lug on the holder having an opening disposed at right 20 angles to the shaft, a tool shaft supported on the holder, a tool mounted on the tool shaft, and a single coil spring having one end thereof fitted in said opening of the lug, said spring having an integral loop in the coiled portion thereof for 25 receiving the shank of the tool.

LÉON DUFOUR.
